UNITED STATES PATENT OFFICE

143,789

DESIGN FOR A TELEPHONE STAND UNIT

Richard G. Bell, Miami, Fla.

Application June 7, 1945, Serial No. 119,951

Term of patent 7 years

(Cl. D74—1)

To all whom it may concern:

Be it known that I, Richard G. Bell, a citizen of the United States, residing at Miami, in the county of Dade and State of Florida, have invented a new, original, and ornamental Design for a Telephone Stand Unit, of which the following is a specification, reference being had to the accompanying drawing, forming part thereof.

On the accompanying drawing:

Fig. 1 is a perspective view of a telephone stand

unit embodying my new design, in normal condition;

Fig. 2 is a plan view thereof; and

Fig. 3 is a perspective view of the unit with the reference list thereof pulled out and exposed to view.

I claim:

The ornamental design for a telephone stand unit, substantially as shown and described.

RICHARD G. BELL.
